C. B. CARTER ET AL

PROCESS OF PRODUCING CHLOR-DERIVATIVES OF METHANE

Filed August 9, 1923

UNITED STATES PATENT OFFICE.

CARNIE B. CARTER AND ALBERT E. COXE, OF PITTSBURGH, PENNSYLVANIA, AS-
SIGNORS TO S. KARPEN & BROS., OF CHICAGO, ILLINOIS, A CORPORATION OF WEST
VIRGINIA.

PROCESS OF PRODUCING CHLOR-DERIVATIVES OF METHANE.

Application filed August 9, 1923. Serial No. 656,487.

To all whom it may concern:

Be it known that we, CARNIE B. CARTER and ALBERT E. COXE, citizens of the United States, residing at Pittsburgh, in the county of Allegheny and State of Pennsylvania, have invented a new and useful Improvement in Processes of Producing Chlor-Derivatives of Methane, of which the following is a specification.

10 This invention relates particularly to the production of the higher chlorides from methane, and more especially to a process which will enable a high yield of methylene chloride to be obtained from methane and chlorine.

15 The improved process can be readily and safely carried on in a closed circuit into which chlorine and methane are continuously fed in suitable proportions, as 20 for example 100 volumes of chlorine to about 46 volumes of methane.

In the practice of the improved process in the preferred manner, one obtains a yield of about 80% methylene chloride (CH_2Cl_2), 25 about 15% chloroform (CHCl_3), and about 5% carbon tetrachloride. In the system which is employed, a mixture of methyl chloride (CH_3Cl) and methane (CH_4) is circulated through a chlorinator, chlorine 30 and methane are fed into the system in suitable proportions, and methylene chloride, chloroform and carbon tetrachloride are taken in liquid form from the system. These products are subjected to fractional distillation to effect separation.

35 The proportions of chlorine and methane which are fed into the system are determined by the respective yields of the higher chlorides.

40 The process may be conveniently described in connection with the accompanying drawing, which represents diagrammatically one form of suitable apparatus for the practice of the process.

45 In the drawing—

A represents a mixer; B, a chlorinator; C, an acid scrubber; D, a gasometer; E, a compressor; F, a condenser; G, a receiver; H, a gasometer; I, a circulating pump; J, a chlorine feed pipe; K, a methane feed pipe; L, a still; M, a storage tank which receives the liquid methylene chloride, chloroform and carbon tetrachloride; and N, a suitable check valve, or expansion valve, regulating

the passage of gas from the receiver G to 55 the gasometer H.

The system through which constant circulation takes place in the preferred practice of the process includes the pipe 1 leading to the mixer A; the pipe 2 leading from the mixer to the chlorinator B; the pipe 3 leading from the chlorinator to the acid scrubber C; the pipe 4 leading from the scrubber to the gasometer D; the pipe 5 leading from the gasometer D to the 60 compressor E; the pipe 6 leading from the compressor to the condenser F; the pipe 7 leading from the condenser to the receiver G; the pipe 8 leading from the receiver to the gasometer H, the pipe 8 containing the 65 expansion valve N; the pipe 9 leading from the receiver to the still L; the pipe 10 leading from the still and communicating through the pipe 8 with the gasometer H; and the pipe 11 leading from the gasometer 70 H through the circulating pump I to the pipe 1 which carries the mixture of gases to the mixer A.

The storage tank M receives its supply 75 from the still L through a pipe 12. The pipes J and K are shown connected with the pipes 1 and 11 at point Q.

Assuming that it is desired to operate the system in such a manner as to obtain a yield of about 80% methylene chloride, 15% 80 chloroform and 5% carbon tetrachloride, the gases fed to the chlorinator B will be in about the following proportions: 100 vols. chlorine, 100 vols. methyl chloride, 200 vols. methane.

On the foregoing basis, the system will so operate that the pipe 11 will deliver to the pipe 1 about 253.75 vols. of a mixture of methane and methyl chloride, this mixture being composed of 100 vols. methyl chloride and 153.75 vols. methane. Such a mode of operation requires a feed of 100 vols. chlorine through the inlet pipe J and 46.25 vols. methane through the inlet pipe K.

The ratio of methane to methyl chloride circulating in the system through the pipe 11, it will be noted, is approximately 60 parts methane to 40 parts methyl chloride. That is, the methane is about 50% greater than the methyl chloride.

105 The chlorinator B is of earthenware, quartz or other suitable material, which preferably is maintained at a temperature of 400° C.

to 500° C. The limiting temperatures are in the neighborhood of 350° to something less than 800°. From a practical standpoint, it is not desirable to employ a temperature in excess of 650°. Any suitable means may be employed for maintaining the chlorinator at the desired temperature.

Hydrochloric acid is formed in the process, and this is removed when the gases are 10 passed through the scrubber C. The gases contained in the gasometer D are the four chlorides and methane. By means of the compressor E and the condenser F, the higher chlorides are condensed and passed to the 15 receiver G. The liquefied gases pass through the pipe 9 which is provided with a valve O, which may be a check valve. The methane and the most of the methyl chloride escape from the receiver, and passing the 20 check valve N, enter the gasometer H. Some of the methyl chloride, and perhaps small quantities of methane, may pass into the still L. The still L is operated at a suitable temperature to expel the methyl chloride and 25 any entrapped methane, so that the same will pass into the gasometer H. The liquid methylene chloride, chloroform and carbon tetrachloride pass from the still into the 30 storage tank M. Any suitable means may be employed for effecting separation of the liquefied products derived from the operation of the system.

The process described obviates the destruction of the methane molecule by the 35 reaction which forms carbon and hydrochloric acid. Hence, the method may be practiced without danger of a reaction of explosive violence. Moreover, the process enables a high yield of methylene chloride 40 to be obtained in a very simple manner. In order to secure large yields of methylene chloride, it is necessary to employ relatively high chlorine concentration, or to resort to some method for the removal of methylene 45 chloride, as it is formed, from the system. This latter course is the one adopted in the practice of the present process. Two results follow from this: First, the danger of reaction of explosive violence is obviated; and 50 second, the formation of excessive amounts of chloroform and carbon tetrachloride is avoided. This is of importance where the main product desired is methylene chloride.

In the practice of the process, the system 55 may be considered as filled initially with a mixture of methane and methyl chloride in the ratio of about 60 parts methane to about 40 parts methyl chloride. If desired, the system may be filled initially with methane, 60 and chlorine may be fed gradually into the system until the desired mixture is obtained, the chlorinator operating to effect the chlorination of the methane until the desired proportions are obtained. The proportions of the methane and chlorine feeds will then de-

termine the relative proportions of the liquid products accumulating in the storage tank M.

A pressure of between 10 and 15 atmospheres is a suitable pressure to employ at 70 the compressor.

The mixer A may be of any suitable construction. A cylinder will answer, but preferably some suitable means is employed for effecting a more thorough mixing. 75

The proportions of the gases in the system may be varied. Thus, the gases passing through the pipe 1 may be composed of from 10 to 30% chlorine and 90% to 70% methane and methyl chloride. It is preferred, however, to employ about 25% chlorine. In the specific example given above, calculated to give a yield of about 80% methylene chloride, 15% chloroform and 5% carbon tetrachloride, the chlorine and methyl chloride 85 are fed to the chlorinator in about equal volumes, together with the desired amount of methane. It is preferred to use the chlorine and methyl chloride in about these proportions; and, in practice, these are about the 90 proportions which will be maintained, even though the percentage of chlorine employed in the mixture fed to the chlorinator be changed within the limits stated in the present paragraph. 95

Rapid passage of the gases through the chlorinator is desirable, inasmuch as the chlorine will be consumed within a few seconds, at the temperatures employed.

From the description given, it will be 100 understood that the improved process can be practiced in a highly satisfactory manner by employing a continuous feed to the system of in the neighborhood of two parts methane to one part chlorine. Such a practice is thoroughly safe and yields a high percentage of methylene chloride in the liquid recovered from the system. 105

The foregoing detailed description has been given for clearness of understanding 110 only, and no unnecessary limitations should be understood therefrom, but the appended claims should be construed as broadly as permissible in view of the prior art.

What we regard as new, and desire to secure by Letters Patent, is:

1. The process of producing the higher chlorination products of methane which comprises passing a mixture comprising methyl chloride, methane and chlorine through a 120 reaction chamber maintained at elevated temperature, the methyl chloride and chlorine being present in approximately equal volumes.

2. The process of producing the higher 125 chlorination products of methane which comprises passing a mixture comprising methyl chloride, methane and chlorine through a reaction chamber maintained at a temperature between 350° C. and 650° C., 130

the methane being in excess of the methyl chloride and the latter about equal to the chlorine fed into the reaction chamber.

3. The process of producing the higher chlorination products of methane which comprises passing a mixture of methyl chloride, methane and chlorine through a reaction chamber maintained at elevated temperature, the gases being taken in proportions of 10 from 10% to 30% chlorine and 70% to 90% aggregate of methyl chloride and methane the methyl chloride and chlorine being employed in approximately equal volumes.

4. The process of producing the higher chlorination products of methane which comprises passing a mixture comprising methyl chloride, methane and chlorine through a reaction chamber maintained at elevated temperature, the gases being employed in proportions of from 10 to 30% chlorine and 70 to 90% aggregate of methyl chloride and methane, the methane being in excess of the methyl chloride and the latter being about equal in volume to the chlorine.

5. The process of producing the higher chlorination products of methane which comprises passing a mixture comprising methyl chloride, methane and chlorine through a reaction chamber maintained at a temperature between 350° C. and 650° C., removing the higher chlorination products formed in the passage through the reaction chamber and passing the remaining methyl chloride and methane together with fresh supplies of chlorine and methane through the reaction chamber, the methyl chloride and chlorine being employed in substantially equal volumes.

6. The process of producing the higher chlorination products of methane which comprises passing a mixture comprising methyl chloride, methane and chlorine through a reaction chamber maintained at a temperature between 350° and 800° C., removing the hydrochloric acid formed, removing the higher chlorination products formed, and returning the remaining gases together with fresh supplies of chlorine and methane through the reaction chamber, the chlorine and methyl chloride being fed to the reaction chamber in substantially equal volumes.

7. The process of producing the higher

chlorination products of methane which comprises circulating a mixture of methyl chloride and methane through a circuit which includes a chlorinator, introducing fresh supplies of chlorine and methane into the circuit, and removing the higher chlorination products from the circuit, the methyl chloride and chlorine being fed to the chlorinator in substantially equal volumes.

8. The process of producing methylene chloride which comprises circulating a mixture comprising methyl chloride and methane through a closed system which includes a chlorinator, removing from the system the methylene chloride formed, and retaining the methyl chloride in the system and introducing into the system fresh supplies of chlorine and methane.

9. The process of producing methylene chloride which comprises circulating a mixture comprising methyl chloride and methane through a closed system which includes a chlorinator, removing from the system the methylene chloride formed, and retaining the methyl chloride in the system and introducing into the system fresh supplies of chlorine and methane, the chlorine introduced being in excess of the methane.

10. The process of producing methylene chloride which comprises circulating a mixture comprising methyl chloride and methane through a closed system which includes a chlorinator, removing from the system the methylene chloride formed, and retaining the methyl chloride in the system and introducing into the system fresh supplies of chlorine and methane, the chlorine being at least twice the proportion of the methane.

11. The process of producing the higher chlorination products of methane which comprises circulating a mixture comprising methyl chloride and methane through a system which includes a chlorinator, introducing fresh supplies of chlorine and methane into said system, removing the acid formed, and condensing the higher chlorination products and removing them from the system and retaining in the system the methyl chloride.

CARNIE B. CARTER.
